LIPSTICK AND CIGARETTE HOLDER

Samuel M. Peck, New York, N. Y.

Application January 7, 1938, Serial No. 183,779

4 Claims. (Cl. 131—178)

The present invention relates to cigarette holders and, more particularly, to an improved cigarette holder which may be used in combination with a mechanical device. More specifically, the invention relates to a combined cigarette holder and lipstick in which the cigarette holder serves as a case for a lipstick of the type which may be advanced mechanically, said holder being provided with means to operate the lipstick mechanism.

An object of this invention, accordingly, is to provide a cigarette holder adapted to encase a mechanical device such as a lipstick.

Another object of the invention is to provide a cigarette holder of the above type wherein the component parts can be moved with respect to each other and are so constructed that the device is operable as a cigarette holder at all times. A further object of the invention is to provide a cigarette holder of this type wherein the relatively movable parts may be utilized to operate the encased mechanical device.

According to one embodiment of the invention, a cigarette holder is formed in three parts including a stem, a body, and an end piece. The body is formed with an opening to receive and position a lipstick of the type which may be advanced mechanically. The stem is removably secured to the body and operates as a cap for the lipstick. The end piece is maintained rotatably in adjacent relationship to the body by a permanent connection between said end piece and the lipstick mechanism. In such a construction, the lipstick may be advanced by rotating the end piece with respect to the body. A locking device may be provided to prevent accidental rotation of the end piece, the latter having the usual opening to receive the end of a cigarette. To provide an operative smoke tube in all relative positions of the stem, body, and end piece, circular troughs are formed in the elements and communicate with the sections of the smoke tube. By reason of the circular troughs, effective communication is maintained between the tip and the opening for the cigarette regardless of the relative position of the stem, body, and end piece.

The novel features considered characteristic of the invention are set forth with particularity in the appended claims. The invention itself, however, both as to its construction and its method of operation, together with additional objects and advantages thereof, will best be understood from the following description of a specific embodiment when read in connection with the accompanying drawing, in which:

Figure 1 is a side view in cross-section of the cigarette holder and lipstick;

Figure 2 is a view similar to Figure 1 in which the stem has been removed from the holder and the end piece has been given a half turn;

Figure 3 is a top view of the device with the stem removed;

Figure 4 is a cross-sectional view taken along a line corresponding to 4—4 of Figure 1 and looking in the direction of the arrows;

Figure 5 is a side view showing the locking device;

Figure 6 is a side view of the tube encasing the lipstick; and

Figure 7 is a side view of the lipstick.

Referring to the above drawing in which like numbers are used to designate like parts throughout, and without limiting the invention to this specific construction, Figure 1 shows the assembled cigarette holder having a stem 1, a body 20 member 2, and an end piece 3. The stem 1 is provided with a shoulder 4 and a threaded opening 5 to receive the end of the body member 2, a smoke tube 6 being provided to extend between the tip 7 and the shoulder 4 of the stem. A gasket 8 is 25 provided in the upper surface of the opening 5 to act as a sealing means for the lipstick compartment 9 hereinafter described.

The lipstick 10 is inserted in a holder 11 having an extension 12 formed thereon. The lipstick holder is journaled in a tubular frame 13 having a spiral slot 14 to receive the extension 12. The lipstick and frame are received in a tubular compartment 9 in the body member 2. A slot 15 is formed on the side of the compartment 9 to receive and guide the extension 12. A boss 16 is formed at the end of the compartment to position the end of the frame 13.

The body member 2 has a shoulder 18 and a threaded portion 17 to fit and position the adjacent end of the stem 1. The other end of the body member 2 is formed with an inset portion 19 at its periphery to receive and position the flange 24 on the end piece. A groove 21 having inwardly extending sides is provided adjacent the inset portion 19 to position slidably a wedge 20 having similarly formed sides.

A smoke conveying tube 22 extends through the body member 2, adjacent and substantially parallel to the lipstick compartment and terminates in 50 a circular trough 23 formed on the surface of the shoulder 18.

The end piece 3 is provided with an extension 31 to fit the adjacent end of the body member 2, and a cigarette receiving recess 25 communicating 55

with upwardly and outwardly extending smoke conveying tubes 26 which terminate in a circular trough 27 adjacent the tube 22. A bolt 28 and nut 29 are centrally located to secure the end piece to the frame 13.

5 A slot 30 is formed at a point on the upper periphery of the end piece so located that it will receive the wedge 20 when the end piece is turned to a closed position as indicated in Figure 1.

10 It will be seen that when the end piece 3 is rotated with respect to the body member 2, the frame 13 will be turned and the coaction between the extension 12 and the slots 14 and 15 serves to advance the lipstick. The stem 1 is removable by reason of the threaded connection 5 to permit such advancement. By reason of the circular troughs 27 and 28 and tubes 6, 26, and 22, a continuous smoke passage is provided between the tip 7 and the cigarette recess 25 regardless of the 20 relative angular position of the stem 1, body member 2, and end piece 3.

25 The above construction provides a cigarette holder suitable to encase a mechanical lipstick, and one that remains operable at all times. Considerable convenience and economy of space is provided thereby in a manner which is pleasing and acceptable to the eye.

30 Although a certain form of the invention has been shown and described, many modifications thereof are possible and will suggest themselves to persons skilled in the art. For example, a variety of forms of mechanical lipstick might be utilized, or the circular troughs described might be located on either of the abutting surfaces. 35 The invention, therefore, is not to be restricted except insofar as is necessitated by the prior art and by the spirit of the appended claims.

I claim:

1. A cigarette holder formed of a plurality of 40 parts and having an axial recess adapted to receive a lipstick or the like, comprising a stem, a body portion, and an end piece, the body portion being formed with a smoke tube offset with respect to the axis thereof, the end piece being formed with a cigarette recess, means to secure 45 the end piece rotatably to the body portion means to secure the stem portion removably to the body portion, and communicating means in the stem and end piece communicating with the offset tube

in the body portion regardless of the relative positions of the stem, end piece and body portion.

2. A cigarette holder formed of a plurality of 5 parts and having an axial recess adapted to receive a lipstick or the like, comprising a stem, a body portion, and an end piece, the body portion being formed with a smoke tube offset with respect to the axis thereof, the end piece being formed with a cigarette recess, means to secure the stem portion removably to the body portion, 10 means to secure the end piece rotatably to the body portion, ducts in the stem and end piece, and means providing continuous communication between the offset tube and said ducts regardless of the relative positions of the stem, body member, and end piece.

3. A cigarette holder formed of a plurality of 20 parts and having an axial recess adapted to receive a lipstick or the like, comprising a stem, a body portion, and an end piece, the body portion being formed with a smoke tube offset with respect to the axis thereof, the end piece being formed with a cigarette recess, means to secure the stem portion removably to the body portion, 25 means to secure the end piece rotatably to the body portion, ducts in the stem and end piece, said body portion and end piece being formed with annular grooves between the smoke tube and ducts to provide a continuous smoke passage-way regardless of the relative angular positions 30 of the stem, body member and end piece.

4. A cigarette holder formed of a plurality of 35 parts and having an axial recess adapted to receive a lipstick or the like, comprising a stem, a body portion, and an end piece, the body portion being formed with a smoke tube offset with respect to the axis thereof, the end piece being formed with a cigarette recess, means to secure the stem portion removably to the body portion, 40 means formed on the end piece extending into said axial recess in the body portion, comprising a shaft capable of transmitting rotational movement from the end piece to the lipstick or the like, means for securing the shaft rotatably to the body portion, and ducts in the stem and end piece 45 communicating with the offset tube in the body portion.

SAMUEL M. PECK.
